72,042

Term of patent 14 years

(Cl. D26—14)

FIG. 1

FIG. 1 is a perspective view of a telephone answering and message recording machine, showing my new design; FIG. 2 is a rear elevational view of the machine shown in FIG. 1; and

FIG. 3 is an elevational view of the right side of the machine illustrated in FIG. 1.

The surface of the left side of the machine is substantially the same as the surface disclosed for the right side.

The dominant features of my new design are shown in solid lines in the drawings.

This application is a continuation of my application D. 62,578 filed October 24, 1960, abandoned subsequent to the filing of this application.

I claim:

The ornamental design for a telephone answering and message recording machine, substantially as shown and described.
